Primary Examiner — Richard E Chilcot(74) *Attorney, Agent, or Firm* — Brooks Kushman P.C.(57) **CLAIM**

The ornamental design for a solar street lamp, as shown and described.

DESCRIPTION

1. Solar street lamp
- 1.1 : Perspective
- 1.2 : Perspective
- 1.3 : Front
- 1.4 : Left
- 1.5: Back
- 1.6: Right
- 1.7:Top
- 1.8: Bottom

Pole-mountable street lamp. no claim is made for the wedge-shaped structures on top that are illustrated with dashed lines; the parallel thin lines and the radial thin lines in the representation represent contours only and do not illustrate an ornamentation or decoration of the surface of the product.

1 Claim, 8 Drawing Sheets(56)
